HACKSAW

Fred F. Williams, Everett, Wash.

Application August 28, 1950, Serial No. 181,779

4 Claims. (Cl. 145—34)

Novel Therapeutic Targets in 17p13.11-17p13.12 Deletions

This invention pertains to hacksaws, and relates particularly to the novel construction of a hacksaw wherein the cutting blade is anchored in adjusted positions firmly against rotation about its longitudinal axis.

It is a principal object of the present invention to provide a hacksaw in which the cutting blade is held securely and firmly in its operative position.

Another object of this invention is the provision of a hacksaw wherein the cutting blade is secured against rotation or other displacement about its longitudinal axis.

Another object of this invention is the provision of a hacksaw, the blade of which may be adjusted to operative positions both in the plane of the frame and at right angles thereto.

Still another object of this invention is the provision of a hacksaw which is adjustable to accommodate blades of different lengths.

Another object of this invention is the provision of a hacksaw which is adjustable to a keyhole type saw useful when working in a confined environment.

Still another object of this invention is the provision of a hacksaw, the blade of which may be secured against rotation without binding of the sawing mechanism.

the securing mechanism.

Still another object of this invention is the provision of a hacksaw having the foregoing advantages, yet being of simple, inexpensive construction.

These and other objects and advantages of the present invention will appear from the following detailed description taken in connection with

the accompanying drawing, in which:
Fig. 1 is a side view of a hacksaw embodying the

Fig. 2 is a side view of a modified form of hack-

saw embodying the features of this invention;

The hacksaw of the present invention includes the main body section 1 provided at one end with a hand grip 2. In the embodiment illustrated, the main body section is constructed of metal bent, as shown in Fig. 3, to form a channel member of U-shaped cross section. An extension member 3 is proportioned to be received slidably within the forward end of section 1, i. e. the end opposite handle 2. Notches 4 provided at spaced intervals along the extension 3 detachably engage the pin 5 secured between the sides of the channel member 1 at the forward end of the lat-

ter. In this manner, the extension 3 may be telescoped within the main body 1 and secured detachably by the notches and pin. The main body 1 and extension 3 thus form a frame of variable length upon which to support the cutting blade 6.

blade 6. Intermediate the ends of the main body section 1, there is a lateral frame extension such as the anchor arm 7 firmly secured by rivets 8. The 10 arm projects laterally from and in the plane of the section 1 in the direction of the terminal end of the handle 2. An adjusting lever 9 is mounted forwardly of and adjacent the anchor arm 7 by means of pivot pin 10 secured between the sides 15 of the body section 1. The adjusting lever is provided with an elongated slot 11 extending obliquely with respect to its longitudinal axis, the said slot receiving the pivot pin 10, as shown. A threaded adjustment screw 12 projects rearwardly 20 toward handle 2 from the lever 9 and extends slidably through a hole 13 provided in the anchor arm. As indicated in the drawing, the hole 13 is preferably elongated in the direction of the longitudinal dimension of the anchor arm to accommodate the slight pivot arc of the adjusting 25 lever 9.

An adjusting wing nut 14 is threaded upon the screw 13. The forward end 15 of the nut is rounded for abutment with the anchor arm 7. In this manner, the nut may be tightened against the anchor arm when the screw is positioned obliquely with respect to the latter without causing binding of the parts.

Lugs 16 and 17 project laterally from the sides of the terminal end of extension 3 and the adjusting lever 9, respectively, to receive the apertured ends of the cutting blade 6. A second lug 18 is similarly provided on the lever 9 to accommodate the assembly shown in Fig. 2.

40 The terminal end of extension 3 is bent at a right angle to form a flange 19 from which the lug 20 projects. In similar manner, the adjusting lever 9 is bent to form flange 21 supporting the lug 22. The lugs 20 and 22 accommodate 45 installation of the cutting blade 6 in a plane extending perpendicular to the plane of the frame.

50 Referring now to Fig. 1 of the drawing, the cutting blade 6 is installed upon the frame in the following manner: Wing nut 14 is unthreaded toward the end of screw 12 sufficiently to pivot the lever 9 toward the end of extension 3 and draw the lugs 16 and 17 together a distance which will permit mounting of the blade 6 thereon. The 55 nut 14 is then threaded onto screw 12 to draw

the lever 9 rearwardly and secure the blade between the said lugs. As the nut is tightened, the lever 9 shifts automatically relative to the anchor arm 7 by virtue of the slot 11, whereby to align the screw 12 properly within the hole 13 in the anchor arm.

In the modification shown in Fig. 2, the installation of the cutting blade 6 is substantially as described hereinbefore with the exceptions that the modified extension 3 is used and the blade is mounted at one end upon lug 18. This construction permits the use of the hacksaw for cutting in confined spaces.

It is to be noted that, in both embodiments, the lever 9 is stabilized against lateral movement by pin 10 and screw 12. As a consequence, the blade 6 is prevented from rotating about its longitudinal axis, thus insuring the cutting of a true course along an intended line.

From the foregoing description, it is apparent that the present invention provides a hacksaw of sturdy but simplified construction and which accommodates with facility and speed the installation and removal of cutting blades. The provision of the adjusting lever, its attached adjusting screw and the anchor arm insures the positive attachment of the cutting blade to the frame and obviates the possibility of displacement of the blade during the cutting operation.

It will be apparent to those skilled in the art that various modifications and changes may be made in the structural details described hereinbefore without departing from the scope and spirit of this invention. Accordingly, the foregoing description is to be considered as merely illustrative, the scope of the present invention being defined by the appended claims.

Having now described my invention and the manner in which the same may be used, what I claim as new and desire to secure by Letters Patent is:

1. A hacksaw comprising a frame, an anchor arm firmly secured to and projecting from the frame, an adjusting lever having a slot therein extending obliquely to its longitudinal axis, pivot means extending through said slot and securing the lever adjustably to the frame, adjusting means releasably interengaging the anchor arm and lever adjacent their free ends, and means on the frame and adjusting lever for detachably mounting a cutting blade therebetween.

2. A hacksaw comprising a frame, an anchor

arm firmly secured to and projecting from the frame and having a hole therein adjacent its free end, an adjusting lever having a slot therein extending obliquely to its longitudinal axis, pivot means extending through said slot and securing the lever adjustably to the frame, an adjusting screw on the lever extending slidably through the hole in the anchor arm, and means on the frame and adjusting lever for detachably mounting a cutting blade therebetween.

3. A hacksaw comprising a frame, an anchor arm firmly secured to and projecting from the frame and having an elongated hole therein adjacent its free end, an adjusting lever having a slot therein extending obliquely to its longitudinal axis, pivot means extending through said slot and securing the lever adjustably to the frame, an adjusting screw on the lever extending slidably through the hole in the anchor arm, and means on the frame and adjusting the lever for detachably mounting a cutting blade therebetween.

4. A hacksaw comprising a frame, an anchor arm firmly secured to and projecting from the frame and having a hole therein adjacent its free end, an adjusting lever having a slot therein extending obliquely to its longitudinal axis, pivot means extending through said slot and securing the lever adjustably to the frame, an adjusting screw on the lever extending slidably through the hole in the anchor arm, a nut engaging the screw for abutment with the anchor arm, said nut being rounded on the end abutting the anchor arm to permit angular positioning of the screw relative to the anchor arm, and means on the frame and adjusting lever for detachably mounting a cutting blade therebetween.
